COIN SORTER

Roger M. Brewster, 1921 Millbrook Drive,
Salt Lake City, Utah 84106

Filed Oct. 21, 1970, Ser. No. 25,592

Term of patent 14 years

Int. Cl. D20—⁹⁹

U.S. Cl. D52—4

FIG. 1

FIG. 2

FIG. 1 is a perspective view of a coin sorter showing my new design;

FIG. 2 is a top plan view thereof;
 FIG. 3 is a right side elevational view thereof;
 FIG. 4 is a left side elevational view thereof;
 FIG. 5 is a front elevational view thereof;
 FIG. 6 is a rear elevational view thereof; and
 FIG. 7 is a bottom plan view thereof.

I claim:

The design for a coin sorter, as shown.
